UNITED STATES PATENT OFFICE.

BERTHA JACOB, OF NEW YORK, N. Y.

WINDOW-CHAIR.

SPECIFICATION forming part of Letters Patent No. 404,855, dated May 28, 1889.

Application filed January 30, 1889. Serial No. 298,115. (No model.)

To all whom it may concern:

Be it known that I, BERTHA JACOB, of New York city, New York, have invented an Improved Window-Chair, of which the following is a specification.

This invention relates to a window-chair that may be folded together when not in use.

The invention consists in the various features of improvement more fully pointed out in the claim.

In the accompanying drawings, Figure 1 is a perspective view of my improved window-chair. Fig. 2 is an end view thereof, and Fig. 3 an end view showing it folded.

5 The letter *a* represents the seat of a window-chair, to which is hinged the back *b*.

c c' are the upper and lower sections of the arm-rest pivoted to one another and to the back and seat, respectively.

20 To the seat *a* as well as to the back *b* there are secured the lower ends of chains *d*, connected on top to a ring *e*. To this ring there is also connected a chain, *f*, terminating in a hook, *f'*. In use the chair is placed with its

25 front edge against a window-frame, A. The seat *a* is connected to this frame by means of

a snap-hook, *g*, and a staple, *g'*. Each of the two chains, *f*, is passed through an eye, *h*, on the side of the window-frame, and then the hooks *f'* are made to engage one of the chain-links. Thus the window-chair may be quickly and securely locked in place. When in place, it can be used with safety by persons who wish to wash the window, as they will be prevented from falling down.

30 When the chair has been removed from the window, it may be compactly folded together, as in Fig. 3.

What I claim is—

40 The combination of a seat with a pivoted back, sectional arm-rests pivoted to the seat and the back, chains *d*, secured to seat and back and secured at their upper end to ring *e*, chains *f*, secured to said ring and carrying hooks *f'*, and with the snap-hook *g* secured 45 to the seat, the hook *g* and chains *f* being adapted to engage staples secured to the window-frame, substantially as specified.

35 BERTHA JACOB.
